(57) **CLAIM**

The ornamental design for an archery dart board, as shown and described.

DESCRIPTION

FIG. 1 is a front top perspective view of the archery dart board;

FIG. 2 is a front view of the archery dart board;

FIG. 3 is a back view of the archery dart board;

FIG. 4 is a left side view of the archery dart board;

FIG. 5 is a right side view mirror exact of the archery dart board;

FIG. 6 is a top view of the archery dart board;

FIG. 7 is a bottom view mirror exact of the archery dart board;

FIG. 8 is a first front perspective in an environment of use; and,

FIG. 9 is a second front perspective view in an environment of use.

In the drawings the broken lines depict environmental subject matter that forms no part of the claimed design.
